UNITED STATES PATENT OFFICE.

HOWARD F. WOODFIN, OF RUTLAND, VERMONT.

DESIGN FOR A BUTTON.

48,576.

Specification for Design. Patented Feb. 15, 1916.

Application filed December 1, 1915. Serial No. 64,593. Term of patent 3½ years.

To all whom it may concern:

Be it known that I, HOWARD F. WOODFIN, a citizen of the United States, residing at Rutland, in the county of Rutland and State of Vermont, have invented a new, original, and ornamental Design for Buttons, of which the following is a specification, reference being had to the accompanying drawing, forming part thereof.

The figure is a plan view of a button, showing my new design.

I claim:

The ornamental design for a button, as shown.

HOWARD F. WOODFIN.

Witnesses:

PERCY W. ADAMS,
FREEMAN E. PLUE.
